UNITED STATES PATENT OFFICE.

CLEMENT W. MICHAEL, OF RACINE, WISCONSIN, ASSIGNEE TO J. I. CASE PLOW WORKS, OF RACINE, WISCONSIN, A CORPORATION.

CULTIVATOR.

1,084,557.

Specification of Letters Patent.

Patented Jan. 13, 1914.

Application filed October 4, 1909. Serial No. 520,964.

To all whom it may concern:

Be it known that I, CLEMENT W. MICHAEL, a citizen of the United States, and a resident of Racine, county of Racine, and State of Wisconsin, have invented certain new and useful Improvements in Cultivators, of which the following is a specification.

The invention relates to wheeled cultivators and more particularly to that type in which the cultivator beams are connected to a counterbalancing seat-bar, so that the rider may raise and lower the beams without the use of shift-levers or the like.

The invention seeks to provide a counterbalancing spring in connection with the seat-bar and cultivator beams, the tension of which can be readily regulated in accordance with the weight of the different riders.

In prior constructions, the machine has been adapted for riders of different weight by providing adjustable connections between the counterbalancing seat-bar and the cultivator beams which vary the leverage of the seat-bar upon the beams. Such an adjustment, however, varies the throw of the cultivator beams and seat-bar, whereas the present improvement provides a machine in which the cultivator beams are counterbalanced by the combined action of a spring and the weight of the rider and means are provided for varying the tension of the spring in accordance with the weight of the rider, while the connections and the throw of the seat-bar and beams remain the same.

The invention also seeks to provide depth-regulating caster wheels for the cultivator beams, to provide connections between the cultivator beams and the swinging wheel sections of the arched axle and to otherwise improve and simplify this type of cultivator.

The invention consists in the features of improvement hereinafter set forth, illustrated in the preferred form in the accompanying drawings and more particularly pointed out in the appended claims.

In the drawings, Figure 1 is a plan view of the improved cultivator. Fig. 2 is a longitudinal section on the line 2-2 of Fig. 1 with the parts in working position. Fig. 3 is a side elevation with the near wheel removed and showing the parts in their elevated or riding position. Fig. 4 is a rear

view of the central portion of the wheel axle with parts shown in section on the line 4-4 of Fig. 1. Fig. 5 is a detail view of the cross-bar at the front of the counterbalancing seat-bar looking in the direction of the arrows 5-5 of Fig. 1. Fig. 6 is a detail view of parts shown in Fig. 5 with the cross-bar shown in section. Fig. 7 is a detail view of one of the depth-regulating caster wheels with parts shown in section on the line 7-7 of Fig. 1. Fig. 8 is a detail section on the line 8-8 of Fig. 7. Fig. 9 is a detail view of the coupling at the forward end of the cultivator beams with parts shown in section on the line 9-9 of Fig. 1. Fig. 10 is a detail side view of parts shown in Fig. 9.

The frame of the machine comprises side-bars 11 that are connected at their forward converging ends by a bracket 12 to the tongue 13. The rear divergent ends of the side-bars 11 are connected to the ends of a transverse member 14 which thus forms part of the frame. This transverse member is preferably in the form of a hollow pipe and also constitutes the central, horizontal crown section of the arched wheel axle within which the upper horizontal portions of the depending wheel sections 15 are swiveled. This transverse member or crown section of the arched axle, as most plainly shown in Fig. 4, is secured to the rear ends of the side frame bars by castings 16 which fit over the ends of the member 14 and are clamped thereto by bolts 17. The castings or brackets 16 are provided with upwardly projecting lugs 18 that are connected to the rear ends of the side-bars 11 by bolts 19. The supporting wheels 20 are journaled upon horizontal spindles at the lower ends of the wheel sections 15 of the arched axle. The upper horizontal ends of the wheel sections extend within the ends of the hollow crown section 14 and are provided with collars 21 that are adjustably secured thereto by set screws 22. These collars are arranged beneath projecting portions of the brackets 16 and are held against lateral movement by depending ribs 23 thereon. By this arrangement, the wheel sections of the arched axle and the wheels carried thereby can shift back and forth relatively to the frame to balance the machine when the cultivator gangs are in their working and riding positions and the wheel

spindles and wheels can also be laterally adjusted in accordance with the varying distances between the rows of plants.

A yoke 24 of usual form is secured to the forward part of the frame. The upper part of the yoke is secured to the rear end of the tongue 13 by a bolt 25 and to the side-bars 11 by bolts 26. The lower ends of the yoke are connected to the tongue and to the forward ends of the side-bars 11 by inclined brace-bars 27. At its lower end, the yoke is provided with outwardly projecting spindles 28 upon which coupling sleeves 29 are rotatably mounted. Couplings 30 are adjustably secured to the sleeves 29 and upwardly-projecting standards 31 at the forward ends of the cultivator beams or gangs are vertically swiveled in the couplings. Each cultivator beam comprises bars 32 connected together in offset relation and secured at their forward ends to the standards 31. The beams are each provided with a series of vertical shanks 33 carrying the cultivating shovels 34. The connections between the standards 31 and the couplings 30 permit the lateral swing of the beams to cultivate different portions of the ground. The beams are also free to shift vertically to and from working position. During this shift, the couplings 30 and sleeves 29 turn upon the horizontal spindle 28 of the yoke 27. The couplings 30 may be adjusted laterally on the sleeves 29 in accordance with the different widths between the rows of plants.

The cultivator beams are counterbalanced and are moved to and from working position by means of a seat-bar that is pivoted intermediate its ends to the frame, carries a rider's seat on its rear end and is connected at its forward end to the beams. In the preferred form shown, the counterbalancing seat-bar comprises front and rear sections, each formed of twin bars. The twin bars 35 of the front section of the seat-bar are parallel for the greater portion of their length (see Fig. 1) and have their forward ends bent inwardly toward each other and connected by a casting or bracket 36. This bracket (see Fig. 5) fits over the forward ends of the bars and is secured thereto by a bolt 37. The rear ends of the twin bars 35 extend between lugs 38 (see Figs. 1 and 4) on a casting or bracket 39 and are connected to the lugs by pivot bolts 40. The bracket 39 fits upon the central portion of the crown section 14 of the arched axle and is firmly secured thereto by U-bolts 41. The rear section of the counterbalancing seat-bar comprises the twin bars 42 that carry the rider's seat 43 at their rear ends. The forward divergent ends of the bars 42 overlap the rear ends of the bars 35 of the front section and the other lugs 38 and pivotally engage the bolts 40. The rear ends of the bars 35

extend beyond the pivot bolt 40 and are provided with lugs 44 fixed thereto and extending beneath the bars 42. The front and rear sections 35 and 42 of the counterbalancing, seat-supporting bar, during the ordinary operation of the machine, shift together about the pivot bolts 40. The one-way connection between the sections, formed by the lugs 44, permits the shift of the rear section 42 with its seat 43 upwardly and forwardly out of the way when the machine is to be shipped or stored.

The cultivator beams are flexibly connected to the ends of a cross-bar 45 that is pivoted to the forward end of the counterbalancing, seat-supporting bar. This cross-bar extends between a pair of upwardly and forwardly inclined lugs 46 on the bracket 36 and is centrally connected thereto by a pivot bolt 47. A pair of brackets 48 are adjustably mounted upon the ends of the cross-bar 45 and are preferably provided with slots 49 through which the cross-bar extends. Adjacent its ends, the cross-bar is provided with a series of notches 50 in its upper edge and the brackets 48 are provided with portions 51 at the upper ends of the slots 49 adapted to engage the notches 50 and hold the brackets 48 in adjusted position. The slot 49 of each bracket is of such size that the bracket can be raised to disengage its portion 51 from the notch 50 and then shifted along the cross-bar into engagement with another of the notches 50. Cotter-pins 52 extend through the ends of the cross-bar 45 and prevent the accidental disengagement of the brackets 48 therefrom. The brackets 48 are held in inclined position by the cross-bar 45 and I-bolts 53 extending therethrough are connected to the upper ends of flexible connecting chains 54 that extend downwardly and rearwardly and are connected at their lower ends to hooks 55 on the beams. Hand-wheels or nuts 56 are adjustably threaded upon the upper ends of the I-bolts 53 and engage the upper portions of the brackets 48. These hand-wheels serve to vary the length of the connections between the cross-bar and the cultivator beams.

The cultivator beams are provided with stirrups 57 that are arranged to be engaged by the feet of the operator when he is in position upon the seat 43. The weight of the operator upon the seat will counterbalance the weight of the cultivator beams, and the operator, by throwing his weight forward or back and by depressing or lifting the beams with his feet, can readily shift the beams to or from working position and he can also guide the beams in lateral direction about the plants. At all times his hands are left free to guide the team.

In cultivators of this type, in which the beams are counterbalanced and raised and lowered by a seat-bar, it is necessary to

adapt the machine for riders of different weight. In accordance with the present invention, this is effected by a spring which assists counterbalancing the cultivator beams. In the preferred form shown, the counterbalancing spring 58 is connected at its forward end to a hook 59 on the bracket 36 and at its rear end is connected to the frame by adjusting means for varying its tension in accordance with the weight of the rider. In the form shown, the spring is connected at its rear end by a hook 60 to the joint of a pair of pivoted toggle links 61 and 62. The toggle link 61 is pivoted to a notched segment 63 that is bolted to the bracket 39 on the crown section of the arched wheel axle. A shift lever 64 is pivoted to the notched segments 63 and the toggle link 62 is pivotally connected to the lever adjacent its pivoted end. The lever 64 (see Fig. 4) is formed of twin members which embrace the notched segment 63 and is provided with a dog 65 for engaging the notches of the segment to thereby hold the shift lever in adjusted position. A spring-held trip 66 for the dog is pivoted to the lever adjacent its upper end. By adjusting the lever 64, the tension of the spring 58 can be readily varied and the beams properly counterbalanced with riders of different weight. The toggle links 61 and 62 serve to increase the leverage of the shifter 64 upon the spring. In prior constructions, it has been common to adapt the machine for different riders to vary the point of connection between the connections or chains 54 and the gangs. This mode of adjustment, however, varies the throw of the gangs and of the counterbalancing seat-bar whereas, with applicant's improved arrangement, the throw of the seat-bar and of the gangs is not changed.

In cultivators of this type, it is difficult to hold the cultivator beams at a uniform working depth. In accordance with the present invention, the beams or gangs are provided with depth-regulating wheels 67 adjustably connected thereto. These wheels are in the form of caster-wheels and are journaled upon the rearwardly inclined lower ends of spindles or standards 68. The upper, vertical portions of the standards or spindles 68 are swiveled or pivoted within brackets 69 and these brackets are adjustably connected to the outside bars 32 of the beams by bolts 70 which extend through vertical longitudinal slots in the brackets. Guide pieces 72 are provided for holding the brackets in upright position. These guide pieces are provided with longitudinal ribs (see Fig. 7) that engage the upper and lower edges of the beam bars 32 and with vertical ribs (see Fig. 8) that engage the side edges of the brackets 69. The caster movement of each wheel 67 is limited by a part 73 that is

connected to the upper end of the standard 68 to turn therewith and is provided with a depending lug 74 arranged between a pair of stop lugs 75 on the upper portion of the bracket 69 (see Figs. 1 and 7). These 70 caster-wheels will accurately determine the working position of the gangs, notwithstanding the fact that the latter are connected and are raised and lowered by the floating or counterbalancing seat-bar. By 75 loosening the nuts on the bolts 70, the caster-wheels can be readily adjusted to vary the working depth of the beams. These depth-regulating caster wheels will not interfere with the lateral movement of the gangs effected by the feet of the operator engaging the stirrups 57.

The vertical shift of the beams to riding position is limited by a stop connection between the counterbalancing seat-bar and the frame. In the form shown, this stop connection comprises two flexible chains 76 which are connected at their forward ends to the frame by the bolts 26 and the rear ends of which are arranged to adjustably 90 engage any one of a series of holes 77 formed in forwardly-projecting ribs 78 on the brackets 48. These flexible chains 76 serve to limit the movement of the seat-bar when it is shifted to raise the gangs as illustrated 95 in Fig. 3. In its working and riding positions, the depending wheel spindles 15 are arranged to shift with the cultivator beams. For this purpose, links 79 are pivotally connected by I-bolts 80 to the lower ends of 100 the wheel sections 15 of the arched axle and, at their forward ends, to the lower ends of a pair of arms 81 that are pivoted on the outer ends of the spindle 28 of the yoke 24. The sleeves 29 on the spindles 28 105 are provided at their outer ends with short depending arms 82, and the arms 81 are adjustably connected to the arms 82 by bolts 83. Each bolt is arranged to extend through one of a series of holes 84 in the 110 arms 81. By thus connecting the depending wheel sections of the arched axle to the couplings at the forward ends of the cultivator beams, the wheels are shifted, as the beams are raised and lowered, and the 115 machine is properly balanced, both in the working position and in the riding position of the beams.

An equalizer bar 86 extends beneath the rear end of the pole 13 and above a strap 86 bolted to the under side of the pole. The equalizer bar is pivoted to the pole and strap by a bolt 88. A pair of bars 89 are pivoted at their upper ends to the ends of the equalizer bar and depend therefrom. The lower ends of the bars 89 are connected by chain links 90 to the arms 81. The bars 88 are provided with a series of holes 91, so that the whiffletree of the team may be connected thereto. The pull of the team 130

upon the arms 81 tends to turn the sleeves 29 on the spindles 28 of the yoke 24 and thus tends to hold the cultivator beams in working position with the shovels thereon 5 in the ground.

The pull of the team upon the tongue assists in raising the gangs or cultivator beams, since the forward shift of the upper ends of the rear sections of the arched axle 10 raises the beams.

It is obvious that numerous changes can be made in the details set forth without departure from the essentials of the invention.

I claim as my invention:—

15 1. In a cultivator, the combination with the frame, of a cultivator beam hung therefrom, a seat-supporting bar connected to said beam to counterbalance the same, a balance spring for bar and beam, and means for adjusting the tension of said spring to adapt the machine to riders of different weight, substantially as described.

20 2. In a cultivator, the combination with the frame, of cultivator beams hung therefrom, a counterbalancing bar having a seat on its rear end, connections between the forward end of said bar and said cultivator beams, a counterbalancing spring for said seat bar and said beams, and a shift-lever 25 for adjusting the tension of said spring having means for releasably locking the same in adjusted position, substantially as described.

25 3. In a cultivator, the combination with the frame, of cultivator beams hung from said frame, a counterbalancing seat-supporting bar pivoted to the frame intermediate its ends and having a seat on its rear end, connections between the forward end of said 30 seat-bar and said beams, a counterbalancing spring interposed between said seat bar and the frame, and means for adjusting the tension of said spring, substantially as described.

35 4. In a cultivator, the combination with the frame, of cultivator beams hung from said frame, a counterbalancing seat-supporting bar pivoted to the frame intermediate its end and having a seat on its rear end, 40 connections between the forward end of said seat bar and said beams, a counterbalance lift spring connected at one end to said seat-supporting bar, an adjusting lever pivoted on the frame and connected to the opposite 45 end of said spring, and means for releasably locking said lever in adjusted position, substantially as described.

50 5. In a cultivator, the combination with a frame and an arched wheel axle having a 55 central portion fixed to the side-bars of said frame, of cultivator beams hung from the forward end of said frame, a counterbalancing seat-supporting bar pivoted between its ends to the central portion of said axle, 60 connections between the forward end of said

seat-bar and said beams, a counterbalancing lift-spring connected at one end to the forward end of said seat-bar, and adjustable means connecting the other end of said spring to the central portion of said axle, 70 substantially as described.

6. In a cultivator, the combination with a frame and an arched wheel axle having a central portion fixed to the side-bars of said frame, of cultivator beams hung from the forward end of said frame, a counterbalancing seat-supporting bar pivoted between its ends to the central portion of said axle, 75 connections between the forward end of said seat-bar and said beams, a counterbalancing lift-spring connected at its forward end to the forward end of said seat-bar, an adjusting lever pivoted on the central portion of said axle and connected to the rear end of said spring, and means for releasably locking said lever in adjusted position, substantially as described.

7. In a cultivator, the combination with the frame, of cultivator beams hung from said frame, a counterbalancing seat-supporting bar pivoted to the frame intermediate its ends and having a seat on its rear end, connections between the forward end of said seat-bar and said beams, a counterbalancing lift-spring connected at its forward end to the forward end of said seat-bar, an adjusting lever pivoted on the frame, jointed toggle links connected to the rear end of said spring and pivoted respectively to said lever and to said frame, and means for releasably locking said lever in adjusted position, substantially as described.

8. In straddle row cultivators, the combination with an arched wheel axle and a frame mounted thereon, of cultivator beams hung on said frame to swing laterally and vertically, a counterbalancing seat bar pivotally mounted on said frame between its ends and having a seat at its rear end, connections between the forward end of said seat bar and said cultivator beams and ground engaging devices connected to each of said beams for limiting the movement of said beams and seat bar to working position, substantially as described.

9. In straddle-row cultivators, the combination with an arched axle and frame mounted thereon, of cultivator beams hung on said frame to swing laterally and vertically, a counterbalancing seat bar pivotally mounted on said frame between its ends and having a seat on its rear end, connections between the forward end of said seat bar and said cultivator beams and adjustable stop connections between the forward end of said seat bar and said frame for limiting the upward movement of said cultivator beams, substantially as described.

10. In straddle row cultivators, the combination with the arched axle, of a frame

mounted thereon, cultivator beams hung on said frame to swing laterally and vertically, a counterbalancing seat bar pivoted on said frame between its ends, connections between the forward end of said seat bar and said cultivator beams, a ground engaging device adjustably connected to each of said beams for limiting the movement of said seat bar and said frame to limit the movement of said bar and said beams to riding position, substantially as described.

11. In straddle row cultivators, the combination with the frame having a yoke at its forward end and an arched wheel axle whereon said frame is mounted, of cultivator beams hung at the forward ends of said yoke to swing laterally and vertically, a seat supporting bar pivoted intermediate its ends on said frame and having its seat on its rear end, connections between the forward ends of said seat bar and said cultivator beams, and a trailing ground engaging device pivotally mounted upon each of said beams and vertically adjustable thereon, substantially as described.

12. In cultivators, the combination with the frame having a yoke at its forward end, and an arched wheel axle whereon said frame is mounted, of cultivator beams hung at their forward ends on said yoke, a seat supporting bar pivoted intermediate its ends on said frame and having a seat on its rear end, a cross-bar centrally pivoted to the forward end of said seat bar, connections between the ends of said cross-bar and said beams, and stop connections between the ends of said bar and the forward portion of said frame for limiting the upward movement of said beams, substantially as described.

13. In a cultivator, the combination with the tongue, and side frame bars secured at their forward ends to said tongue, of an arched wheel axle comprising a central crown-section secured to said side bars and depending wheel sections swiveled in said crown section, a yoke fixed to the forward end of said frame having horizontal spindles at its lower ends, sleeves on said spindles, couplings adjustably fixed to said sleeves, cultivator beams vertically pivoted to said couplings, depending arms adjustably connected to said sleeves, links connecting said arms and the wheel sections of said axle, a counterbalancing bar pivoted on the crown section of said wheel axle and having a seat on its rear end, and connections between the forward end of said bar and said cultivator beams substantially as described.

14. In a cultivator, the combination with a frame, of an arched axle having depending wheel sections swiveled to the frame, cultivator beams hung at the forward ends on the frame to shift vertically and horizontally, a pair of pivoted arms connected to said

beams to swing in vertical planes therewith, connecting links extending between said arms and said wheel sections, a counterbalancing seat-supporting bar pivoted between its ends on the frame and having a seat on its rear end, and connections between the forward end of said seat bar and said beams, substantially as described.

15. In cultivators, the combination with the frame, the counterbalancing seat bar pivoted thereto, and cultivator beams hung from said frame, of a cross-bar centrally pivoted to the forward end of said seat bar, blocks adjustable on the ends of said cross-bar, bolts extending through said blocks at right angles to said bar, adjusting nuts on said bolts, and chains connected to said bolts and said cultivator beams, substantially as described.

16. In cultivators, the combination with the frame, the counterbalancing seat-bar pivoted thereto, and cultivator beams hung from said frame, of a cross-bar centrally pivoted to the forward end of said seat bar, said cross-bar having notches in its upper edge adjacent its ends, slotted blocks adjustably slidably on said bar and having portions at the upper end of the slots thereof for engaging said notches, and flexible connections between said blocks and said beams, substantially as described.

17. In cultivators, the combination with the frame, the counterbalancing seat-bar pivoted thereto, and cultivator beams hung from said frame, of a cross-bar centrally pivoted to the forward end of said seat-bar, blocks adjustable on the ends of said cross-bar, flexible, adjustable connections between said blocks and said beams, and flexible, adjustable stop connections between said blocks and the forward portion of said frame, substantially as described.

18. In a straddle row cultivator, the combination with an arched axle, of a frame mounted on said axle, cultivator gangs hung at their forward ends to the forward end of said frame to swing laterally and vertically, a counterbalancing seat bar pivoted intermediate its ends on said frame, connections between the forward end of said seat bar and said gangs, said gangs having stirrups at their rear ends arranged to be engaged by the rider's feet for raising and lowering the gangs and guiding the same laterally, and ground engaging devices on said gangs to regulate the working depth thereof, said ground engaging devices being swiveled to said gangs to permit the lateral movement thereof, substantially as described.

19. In cultivators, the combination with the frame and cultivator beams hung thereon, of a counterbalancing seat-bar comprising front and rear sections pivoted to said frame at their adjacent ends, said sections having a one-way connection, a seat on said

rear section, and connections between said front section and said beams substantially as described.

20. In cultivators, the combination with the frame, an arched wheel axle having a central portion fixed to said frame, and cultivator beams hung on said frame, of a double seat-bar comprising front and rear sections pivoted at their adjacent ends to the central portion of said wheel axle, said front section extending rearwardly of the pivot point and having lugs extending beneath said rear section, a seat on said rear section, and connections between the forward end of said front section and said beams, substantially as described.

21. In cultivators, the combination with the wheeled frame, of cultivator beams hung thereon, a seat-bar pivoted to said frame intermediate its ends and having a seat on its rear end, flexible connections between the forward end of said seat bar and said beams, and a flexible stop connection between said seat-bar and the frame, substantially as described.

22. In a cultivator, the combination with the frame and supporting wheels therefor, of a pair of cultivator gangs hung at their forward ends to the forward end of said frame to swing laterally and vertically, a counterbalancing seat bar pivoted intermediate its ends on said frame, connections between the forward end of said seat bar and said gangs, ground engaging devices adjustably connected and pivoted to said gangs for limiting the downward movement thereof and of the forward end of said seat bar, and stop connections between the forward end of said seat bar and said frame to limit the upward movement of said gangs and of the forward end of said bar, substantially as described.

23. In a cultivator, the combination with the frame, arched axle and supporting wheels, of cultivator beams hung at their forward ends to the forward end of said frame to swing laterally and vertically, a counterbalancing seat bar pivotally mounted intermediate its ends on said frame, connections between the forward end of said seat bar and said gangs, and adjustable stop connections between the forward end of said seat bar end and frame for limiting the upward movement of said gangs and of the forward end of said beams, substantially as described.

24. In a cultivator, the combination with the frame, arched axle, and supporting wheels, of cultivator gangs hung at their

forward ends to the forward end of said frame to swing laterally and vertically, a counterbalancing seat bar pivoted intermediate its ends on said frame and having a seat on its rear end, connections between the forward end of said seat bar and said gangs, brackets secured to and vertically adjustable on said gangs, and ground engaging devices swiveled in said brackets and serving to limit the downward movement of said gangs and of the forward end of said seat bar, substantially as described.

25. In a cultivator, the combination with the frame, arched wheel axle and supporting wheels, of cultivator gangs hung at their forward ends to the forward end of said frame to swing laterally and vertically, a counterbalancing seat bar pivoted intermediate its ends on said frame and having a seat on its rear end, connections between the forward end of said seat bar and said gangs, said gangs having a limited, independent, vertical and lateral movement and having stirrups on their rear ends arranged to be engaged by the feet of the rider whereby the rider may raise and lower said gangs and guide them laterally when in position on said seat, and ground engaging devices pivoted to and vertically adjustable on said gangs for limiting the downward movement thereof and of the forward end of said seat bar, substantially as described.

26. In a cultivator, the combination with the frame, arched wheel axle and supporting wheels, of cultivator gangs hung at their forward ends to the forward end of said frame to swing laterally and vertically, a counterbalancing seat bar pivoted intermediate its ends on said frame and having a seat on its rear end, connections between the forward end of said seat bar and said gangs, said gangs having a limited, independent, vertical and lateral movement and having stirrups on their rear ends arranged to be engaged by the feet of the rider whereby the rider may raise and lower said gangs and guide them laterally when in position on said seat, adjustable stop connections between the forward end of the seat bar and the frame for limiting the upward movement thereof and of said gangs, and ground engaging devices pivoted to and vertically adjustable on said gangs for limiting the downward movement thereof and of the forward end of said seat bar, substantially as described.

CLEMENT W. MICHAEL.
